PROCESS OF MANUFACTURING VESSELS
AND THE APPARATUS USED

Emil Pfaendler, Olten, Switzerland

Application July 10, 1931, Serial No. 549,954,
and in Germany July 15, 1930

3 Claims. (Cl. 113—49)

The present invention relates to a new and improved process and to improved means for producing hollow-ware from sheet-metal and more particularly to the manufacture of cooking vessels from aluminium, pots, cans etc.

In the manufacture of such vessels it has been necessary up to now to stamp a sheet metal piece to the requisite shape and after being first cupped to draw it into shape by a series of stamping operations according to the depth of the vessel to be produced.

The main object of the invention is to obviate the several steps and to bring the vessel into shape in but one operation whatever the size and height of the vessel may be and to obviate thereby the drawbacks connected with the old processes now in general use.

Another object of the invention is to simplify the tools to draw such vessels and to reduce the time to produce said vessels.

A further object of the invention consists in the provision of means to work the side walls of the vessel, in such a manner that the thickness of the wall is less near the bottom than at its edge.

A still further object is the provision of means whereby the quality of the material worked, its density and hardness etc. is being improved and wherewith simultaneously a polishing of the side walls is being attained.

I attain this and further objects as will appear in the specification by the process and the means as claimed in the appended claims and as described with reference to the drawing.

According to the invention a round sheet metal disc for instance of aluminium held in a composite die in the usual manner is pressed by a former through a die and in immediate succession thereto through an annular die of steel, the former being provided with an annular slanting recess or groove at a certain predetermined distance from the face of the former. By these means the vessel is not only drawn into cylindrical shape, but while it is being drawn metal is squeezed by said annular die and a thickening of the wall of the vessel at its upper edge is simultaneously produced. By the use of the annular steel die in conjunction with the ordinary drawing dies the side wall of the vessel is worked inside and outside, the walls are burnished or polished simultaneously with the shaping thereof. Moreover the sheet metal is highly compressed and the walls are perfectly smooth, no further polishing being necessary. To produce vessels of a given height sheet-metal discs

of less diameter may be used as in the known processes and vessels of any height might be produced in but one drawing operation.

In the drawing the new device is shown in a diagrammatical manner.

Fig. 1 shows the die in a cross-section.

Fig. 2 illustrates a vessel in section produced by the die shown in Fig. 1.

In the drawing 1 denotes a circular disc of sheet metal say of aluminium, which is to be shaped to a vessel shown in Fig. 2. The disc 1 is held at its circumference by a ring 4 which is pressed against the flanged portion 3 of the die A. The die A is arranged within a flange 11 of a bottom plate 12 and rests on an annular die 5 of steel. The die 5 is concentrically arranged with reference to the die A and to the bore 13 of plate 12. In the plate 12 a number of strippers 6 are arranged which rest on coiled springs 14 arranged in radial bores of said plate 12. The ends of said strippers project in the bore 13, their faces are bevelled in such a manner that they are being pressed into the said bores when the vessel is ejected from the die. The annular die 5 is provided with an inwardly projecting ridge 15. With the dies 5, A, co-operates the plunger 7 which is by the press pushed through the dies the metal disc 1 being withdrawn from between the parts 3, 4 and being cupped and shaped in the well known manner. To reduce the tension etc. in the disc the edges 9 and 10 of die and former respectively have to be rounded-off. The plunger 7 is provided with a recess or reduced portion 8, the wall of the recess being slanting.

In operation the plunger 7 by withdrawing the disc 1 from its holding device shapes the disc 1 to a flat bottomed cylindrical vessel. As soon as the so-shaped vessel leaves the die A it enters the annular die 5. The ridge 15 now works on the side wall compresses the metal and moreover squeezes the metal upwards. The displaced metal is pressed into the recessed portion 8 of the plunger 7. The vessel produced by the die is shown in section in Fig. 2. The side wall 16 is thickened at the upper edge at 19 the shape conforms to the reduced portion 8 of the former. By choosing appropriate dimensions of the parts 5, 15, 7 and 8 the thickness of the side wall 16 near the bottom 17 of the vessel 2 is less than that of the bottom 17, or of the disc 1 in the region nearest the bottom while the thickness of the upper edge 19 is equal to and even greater than that of bottom 17. By withdrawing the plunger 7 the strippers 6 catch over the upper

edge of the vessel and strip the latter from the plunger 7.

By the device described vessels can be easily produced in but one drawing operation the height of which is equal to or in excess of the diameter of the vessel. The side walls of the vessel 2, the inner and the outer are perfectly smooth, the walls are free of flaws and non-porous and no subsequent polishing operation is necessary. The density of the material is materially increased and by using aluminium its tenacity is for instance increased from 21.5 kg/cm² to 43 kg/cm².

I am aware that certain details may be varied through a wide range without departing from the principle of this invention, and I therefore do not purpose limiting the patent granted otherwise than necessitated by the prior art.

What I wish to secure by U. S. Letters Patent, is:—

1. The method of drawing metal and forming hollow ware therefrom, consisting in forcing a blank through a die having an inwardly extending ridge spaced from its lower side by means of a plunger having an upwardly tapering upper portion, spaced from its lower end, so that the portion of the blank forming the wall of the hollow ware article is progressively thickened and the diameter of the space within the wall progressively decreased upwardly as the upwardly

tapered portion of the plunger passes the ridge of the die.

2. Apparatus for drawing metal and forming hollow ware therefrom, comprising a die having an inwardly extending ridge spaced from its lower side, and also spaced from its upper side and the upper portion of the face of which is curved and gradually diametrically contracts downwardly and the lower portion of which gradually diametrically expands downwardly, and a plunger arranged to force and draw a blank downwardly through the die, said plunger having an upwardly tapered portion so spaced from its lower end as to pass below the ridge of the die when a drawing stroke is imparted to said plunger. 80

3. Apparatus for drawing metal and forming hollow ware therefrom, comprising a die having an inwardly extending ridge spaced from its lower side, and a plunger arranged to force and draw a blank downwardly through the die, said plunger having an upwardly tapered portion spaced from its lower end, a plate, holding the die and having a wall extending thereabove, a die member bearing on the die, held by said wall, and having an outwardly extending flange at its upper 90 end, and a ring arranged to hold a blank between the same and said die member. 95
